UNITED STATES PATENT OFFICE

143,807

DESIGN FOR A CONTROL KNOB OR SIMILAR ARTICLE

Melville Eastham, Cambridge, Mass., assignor to
General Radio Company, Cambridge, Mass., a
corporation of Massachusetts

Application December 6, 1944, Serial No. 116,747

Term of patent 14 years

(Cl. D26—1)

To all whom it may concern:

Be it known that I, Melville Eastham, a citizen
of the United States of America, residing at
Cambridge, in the county of Middlesex and Com-
monwealth of Massachusetts, have invented a
new, original, and ornamental Design for a Con-
trol Knob or Similar Article, of which the follow-
ing is a specification, reference being had to the
accompanying drawing, forming a part thereof.

Fig. 1 is a front elevation of a control knob
showing my new design; and

Fig. 2 is a side elevation.

I claim:

The ornamental design for a control knob or
similar article, substantially as shown.

MELVILLE EASTHAM.
